(57) **CLAIM**

The ornamental design for a shoe base, as shown and described.

DESCRIPTION

FIG. 1 is a perspective view of a shoe base according to the present invention;

FIG. 2 is a perspective lateral side view of the shoe base of FIG. 1;

FIG. 3 is a perspective medial side view of the shoe base of FIGS. 1-2;

FIG. 4 is a top perspective view of the shoe base of FIGS. 1-3;

FIG. 5 is a bottom perspective view of the shoe base of FIGS. 1-4;

FIG. 6 is a front perspective view of the shoe base of FIGS. 1-5; and,

FIG. 7 is a rear perspective view of the shoe base of FIGS. 1-6.

The broken lines shown in the Figures are for environmental purposes only and form no part of the claimed design.
